VENETIAN BLIND CONSTRUCTION

Glenn L. Sherwood, Benton Harbor, Mich.

Application April 6, 1945, Serial No. 586,905

9 Claims. (Cl. 160—168)

1

This invention relates to Venetian blinds, and particularly to a head box construction of a Venetian blind for tilting the slats and also for raising and lowering the slats.

Among the objects of the present invention is to provide a Venetian blind construction which will permit a manufacturer to fabricate parts of the head box construction completely finished, and other parts, such as the ornamental front panel and a part of the rod or driving mechanism which drivingly interconnects the slat tilting mechanism and the slat raising and lowering mechanism, as finished strip material which can be sold to a subassembler along with the finished parts, whereby the subassembler can then cut the continuous strip material to exact dimensions according to the specification of any particular installation, can then assemble the completed head box, utilizing the already fabricated parts that come from the main manufacturer, by which construction it is only necessary to keep a number of the completed tilting boxes and raising and lowering boxes on hand, plus a certain length of the strip material, thereby greatly saving expense.

Yet another object of the invention resides in providing a head box construction including mounting end brackets and a separable ornamental front panel and back panel, plus an actuator rod, there being means for quickly and easily assembling all of these parts to provide a complete head box.

Yet another object of the invention resides in providing means for crimping a length of sheet metal front panel to the assembled tilting and raising and lowering boxes in connection with the end brackets, whereby to provide a complete head box for a Venetian blind.

Yet another object of the invention resides in providing a head box for a Venetian blind whereby the principal mechanism for tilting the slats is contained in one completed assembly and the principal mechanism for controlling the slat lifting is contained in another completed assembly, said members being rigidly interconnected in spaced relation and by an elongated rigidifying member for interconnecting the portions of the assemblies to spaced apart stationarily mounted end brackets, there being an ornamental front panel for covering the front of the assembly, which front panel is detachably crimped to the end bracket.

Another object of the invention is to provide a head box for a Venetian blind wherein the tilting mechanisms are economically built as separate assemblies by quantity production methods

2

and are designed to contain all the more or less complicated mechanisms involved in such devices, and which assemblies are constructed to form a structural part of the head box to be completed by the attachment of one or more separate parts that are easily cut to the proper length to suit the individual window width.

Yet another object resides in the construction of the end mounting brackets whereby they may be adjustably mounted on angularly disposed mounting walls, and whereby the head box assembly may be adjustably mounted from and with relation to these end brackets and held in such predetermined position with respect thereto; another feature of the mounting brackets resides in forming them so that they form in effect a continuation of the front panel which is fastened thereto, preferably by crimping, whereby the front panel may be quickly and easily mounted upon the head assembly.

Yet another object of the invention resides in providing a slat tilting box construction having an angularly disposed shaft therein of such construction as to permit the utilization of a larger gear intermeshing with a pinion on the shaft, and also to permit clearance for operating the drum on the shaft without unnecessarily increasing the size of the head box.

Yet another object of the invention resides in the provision of latching mechanism to hold the tilt when the slats are in closed position.

Another object of the invention resides in the construction of the means for holding the tape brackets and restraining the shaft from end play, including means for holding the tape in the bracket for easy assembly and removal.

Yet another object of the invention resides in the means for drivingly interconnecting the mechanism of the tilting box and the tape tilting mechanism.

Another object of the invention resides in the construction of the bottom rail and the end caps, including a lower shield having the purpose of enclosing the rail and securing the tape, and likewise in providing a cap to enclose the end of the shield or rail, said cap having a spacer pin for locking the shield in position.

Yet another object of the invention resides in the means for forming the pulley of sheet metal construction and for assembling the pulley and its driving pinion and shaft within the tilting box, and for connecting it with the toothed sector which operates the tape tilting mechanism.

Yet another object of the invention resides in providing the arrangement of pulleys in the slat

lifting mechanism whereby the cords are maintained in driving relation with the slat lifting mechanism while at the same time eliminating as far as possible the friction incidental to actuating the raising and lowering mechanism of the slats.

Yet another object of the invention resides in the construction of the angularly disposed pulleys disposed in the slat raising and lowering mechanism, whereby the cords for actuating the same are brought out of the box at the underside thereof and close to and below and behind the ornamental front panel, whereby to preserve the unbroken or uncut ornate appearance of the front panel, while at the same time effecting the positioning of the front cords close to the wall thereof for accessibility.

Yet another object of the invention resides in the provision of a simplified mechanism for holding the cord raising and lowering mechanism in adjusted position.

Other and further objects of the invention will be apparent from a perusal of the following specification when taken in connection with the accompanying drawings, wherein:

Figure 1 is a front perspective view of my improved blind;

Figure 2 is a side view thereof;

Figure 3 is a section taken on the line 3—3 of Fig. 4;

Figure 4 is a section taken on the line 4—4 of Fig. 2;

Figure 5 is an exploded view showing the arrangement of the parts;

Figure 6 is a view of the various parts of the head box;

Figure 7 is a view of the holding pawl;

Figure 7a is a view of a shaft and driving sleeve;

Figure 8 is a top or planed section taken on the line 8—8 of Figure 1;

Figure 9 is a vertical section taken on the line 9—9 of Figure 8;

Figure 10 is a section taken on the line 10—10 of Figure 8;

Figure 11 is a section taken on the line 11—11 of Figure 8;

Figure 12 is a plan section taken on the line 12—12 of Figure 1;

Figure 13 is a vertical section taken on the line 13—13 of Figure 12;

Figure 14 is a section taken on the line 14—14 of Figure 12;

Figure 15 is a view of one of the pulley mechanisms; and

Figures 16, 17, 18, 19, 20 and 21 show various constructions of the mechanism for holding the tapes onto the tape lifting mechanism.

In general the improved Venetian blind head box comprises a pair of end brackets adapted to be mounted in the frame of the window or to the vertical side wall or to and on the surface of a horizontal wall. These brackets are mounted in desired spaced relation to accommodate the window width. The box includes two box-like assemblies one of which includes substantially all of the slat tilting mechanism, and the other includes substantially all of the slat raising and lowering mechanism. These two assemblies are fabricated in completed condition at the manufacturing plant and are adapted to be adjustably mounted on and between the two stationary end plates. There is provision for a slight adjustment to accommodate discrepancies in manufacturing. In addition, the construction in-

cludes a rigidifying back plate which is connected to the completed assemblies by means of self-tapping screws. There is also a front panel which is made at the factory and sold in long lengths to the subassembler who at his plant cuts it to predetermined length to suit the dimensions of the particular window installation, and this is then crimped to the front panels of the tilting and raising and lowering boxes, whereby to provide an ornamental front for the head box. The ends of the front panel are shaped and fabricated to form a finished fit with the front ends of the end mounting brackets. In addition, there is provided an elongated rod of angular cross section, which is supplied in lengths and cut to proper length by the subassembler, and this is then put into position whereby drivingly to interconnect the slat tilting mechanism of one of the assembly boxes and the slat raising and lowering mechanism of the other box. The tape shifting mechanism is mounted upon this elongated, angular cross sectioned rod and includes mechanism for quickly mounting or demounting the tapes from the mechanism.

Referring now to the drawings in detail, and particularly to Figure 6, in general the improved head box comprises a fixed, completely fabricated tilting box comprising a front vertical wall of sheet metal 2, a bottom wall 4, and a rear vertical wall 6. The two ends and top are open. The box is formed of any desired gauge sheet metal and carries the slat tilting mechanism hereinafter described. In addition, there is a slat raising and lowering mechanism comprising another box-like assembly having a front vertical wall 8, a bottom wall 10, and a rear vertical wall 12. The two ends and the top of this box-like assembly are open. This assembly includes a part of the slat tilting and raising mechanism.

In addition, the mechanism includes a left end mounting bracket 14 having a top inwardly extending flange 16 and a bottom inwardly extending flange 18, and a rear vertical flange 20. The end at the front is formed on an arc, as shown at 22, for engaging with the front panel hereinafter described. The upper horizontal flange is provided with screw holes 24 and the vertical side wall is provided with screw holes 26. In addition, the bottom horizontal flange 18 is provided with two holes 28 for the reception of a screwdriver when it is desired to utilize the upper holes 24 for fixing the bracket to a horizontal wall such as the ceiling. In addition the bottom flange 18 is provided with a bayonet slot 30 by which the extreme left hand end of the slat tilting box may be mounted and fastened to this end bracket. Similarly there is likewise provided an identical bracket 15 at the opposite end, except that it is reversely faced, as is evident. In addition the front wall 17 of the bracket is provided with screw holes 32. There is also provided an elongated sheet metal strip 34 having an overhanging horizontal flange 36. This strip is provided with holes 38 for self-tapping screws by which the plate 34 is connected by means of the screws registering with the holes 40, 42, 44 and 46 in the rear panel members 6 and 12 of the tilting and lifting boxes, whereby these boxes are rigidly mounted in spaced relation. The two boxes themselves are adapted to have their bottoms 4 and 10 lie upon the two horizontal flanges 18 and 19 of the end brackets and then a screw such as shown at 48 is inserted on the underside of the flanges 18 through

the slots 30 and into a threaded hole 50 on each one of the bottom plates 4 and 10. As shown in Figure 8, the slot 30 of the bottom plate 18 is cut upon a curvature which corresponds with the curvature of the front edge 22 of the end brackets. This arrangement is such that when the front panel 52 which has curved ends 54 and 56 is assembled upon the end brackets, such curved ends 54 and 56 will make a sliding, neat fit with the curved end walls 22 of the end brackets, and due to the fact that these curved walls 22 and 54 are struck on the same arc as the slot 30, irrespective of the adjustment of the bottom plates 4 and 10 with respect to the horizontal plates 18 and 19 of the end plates, 14, the fit between the curved ends 54 and 56 and 22 will always maintain itself.

The front panel 52 is formed of sheet metal. Ordinarily the original manufacturer furnishes this strip in a continuous length which is shipped to the subassembler who then cuts it to lengths according to particular window installation and preferably curves the ends at the job or prior to taking it to the job, so that it will be on the same curvature as the ends 22 of the end brackets. This front panel is preferably formed with upper and lower flanges 58 and 60, see Figure 10, which may be crimped over as at 62 and 64, or other selected places therealong, against the upper edge of the front walls 2 and 8 of the tilting and lifting boxes, whereby normally to hold this panel 52 in position. Thus I have provided means whereby the front panel may be secured to the assembly without defacing or in any way injuring the ornamental aspects of this front panel.

As an additional part of the mechanism there is a bar 66 which is formed in a long strip at the original manufacturing plant and is supplied to the subprocessor as a long continuous bar. This bar is then cut to length by the subprocessor in accordance with the width of the installation required and is then installed to interconnect the tilting mechanism and the lifting mechanism when these mechanisms are assembled by the subprocessor as hereinbefore and hereinafter described. After the bars 66 are cut to the desired length the two tilting brackets shown in Figure 6 are assembled upon this bar. Reference is made to Figure 17. These tilting brackets are disposed one in each end of the boxes, with the bar 66 interconnecting the mechanism. Reference is now made to the tilting box and the lifting box and the construction thereof, and for this purpose Figures 6 and 13 show each of the tilting boxes as comprising the sheet metal boxes, which as hereinbefore mentioned comprises the front vertical wall 2, the bottom horizontal wall 4, and the rear vertical wall 6, the top being open. The front wall is higher than the rear wall. In the tilting box there is mounted a vertically disposed partition 68 which supports a tilting segment 70. This partition has a central bushing 72 which is inserted through a corresponding opening in the partition 68 and on one side the bushing is provided with a shoulder (Figure 9) 74, which overlies the hole in the partition 68. On the opposite side the bushing is provided with a shoulder 76 which accommodates the segment 70 which is held in place by a circular ridge 80 which is turned circumferentially over the inner wall of the tilting segment 70. Thus the bushing carrying the segment is freely rotatable in the opening formed in the partition 68. This bushing in turn is

provided with a square opening 82, see Figure 6, to receive the square rod 66 and therefore when the bushing turns, and due to the square fit, the rod likewise turns. The rod is turned by means of a pinion 84 having teeth which mesh with the teeth 78 of the segment 70. This pinion 84 is mounted on the end of a short shaft 85 which in turn is provided with a semiannular sleeve 86 and welded thereto at 87. A tongue 88 engages a notch 89 on the hub of the pulley 98. The shaft 86 is provided with a reduced end 92 which passes through the pinion 84 and is journaled in a smaller opening 94 in the partition 68 to provide a bearing for that end of the shaft. The semiannular sleeve 86 is provided on its opposite end with a pair of teeth 91 which engage teeth of the pinion 84, and thereby provide a driving connection between the pinion and the pulley 96 and 98. By thus including the shaft 86 I secure a greater gear reduction in the same amount of space without increasing the size of the head box. The shaft 85 has press-fitted thereon the two-piece sheet metal pulley comprising two cup-like abutting parts 96 and 98 which are welded together as at 100. One of these pulleys provides a sleeve 102 to encircle one end of the shaft 85, and the other pulley is provided with an annular wall 104 which is disposed to engage the opposite end of the shaft 90 and also to engage a shoulder 106 on the adjacent end of the shaft 86. By this means the pulley is firmly held in position on the two shafts 86 and 90 which may be held in driving relation by the slot and tongue connection 88. The pulley is provided with the flanges 108 and 110 to hold the cords 112 in place thereon. In general the pulley is assembled upon the shaft 90, the end of the shaft being rotatably inserted in a tongue 114 that is struck up from the bottom wall 4 of the box. After this, the shaft 86 carrying the pinion 84 is inserted to form the slot and tongue connection 88 and the pin 92 is then inserted through the hole in the partition 68 thereby resiliently, yieldingly and rotatably to hold the shaft in turnable position between the tongue 114 and the partition 68. Thus a simple pulley assembly is provided. The pulley is rotated by pulling upon the desired cord 112 whereby to rotate the pulley and rotate the shafts 90 and 86 to rotate the pinion 84 to turn the sector gear 70 and thus turn the squared shaft 66. The bar 66 when tilted by means of the tilting brackets shown in Figure 6, and more specifically shown in Figures 16 to 21 inclusive, will tilt the straps which are connected to the slats of the Venetian blind, simultaneously to give them the proper angle of tilt as is well known. The mounting of these slats is shown specifically in Figures 1 and 2. The ribbons comprising the fabric strips 116 and 118 are connected at spaced desired intervals by transversely disposed cross strips 120 being sewed thereto at 122 and 124. The slats 126 are carried by each one of these cross ribbons 120 so that when the vertically disposed ribbons 116 and 118 are shifted by the mechanism shown in Figures 16 and 17 all of the slats will be simultaneously and correspondingly shifted.

The bottom of the Venetian blind comprises two sheet metal elongated strips 128 and 130, see Figure 5. The upper strip 128 is preferably narrower in cross section than the lower strip 130 and each of these strips is provided with longitudinally extending side flanges 132, 134,

136, and 138, which flanges when the strips rest as shown in Figure 3, will have the flanges 132 and 134 lying within the flanges 136 and 138 of the bottom strip. The bottom portions of the two tapes 116 and 118 are clamped between the two confronting flanges 132 and 134 and 136 and 138 and the two inner ends 140 and 142 are stitched together as at 144. Means is provided for permanently holding the two bottom strips 128 and 130 together and this comprises two end caps 146 and 148 which as shown are flanged to slip over the end portions of the interfitting shields 128 and 130. Each of these shields is provided with an opening through which a pin 150 and 152 is inserted, each pin having a cap 154 on its inner end. That part of the pin which projects through the cap is covered by a rubber cap 156 to prevent noise and rattle. This upper strip 128 is provided with two openings 158 to receive the raising cords 160 and 162, the ends of the cords below the holes 158 being provided with knots 164 to permit assembly. One of the raising cords, such as 160, extends upwardly into the tilting box structure shown in Figure 9 where it passes over a pulley 166, which as shown in Figure 6 is mounted between two struck-up flanges 168 and 170 which are slotted out from the base 4 and pushed up at right angles thereto to form a bearing for the pin 172 on which the pulley is adapted to rotate.

Means is provided for exerting a friction force against the segment to retain the slats on the blinds in a predetermined tilted position. This is best shown in Figures 6 and 11 as comprising a sheet metal bar 174 having a V-shaped hook 176 on one end which engages under a right angle 178 on the partition 68. The bar also has a depressed or folded portion 180 constituting a strip and located between its ends to engage against the circular periphery 182 on the sector 70. This sector 182 as also formed on each end thereof the notches 184 and 186 which determine the limit that the slats can be shifted from one tilted position to the other tilted position whereby the notches 184 and 186 will engage the folded portion 180 of the bar 174 to hold the slats in their extreme tilted positions. A coil spring 188 having one end fixed as at 190 and the other connected as at 192 to the bar 174 keeps a downward tension upon this bar to pull the detent 180 resiliently against the circular periphery 182 of the toothed sector 70 whereby to hold the slats in adjustably tilted position. The notches 184 and 186 engage the detent in extreme adjusted position in either direction, which also provides a yieldable stop to indicate to the operator when the extreme tilted position in either direction has been reached.

The lifting box shown in Figures 6 and 12 to 15 inclusive, like the tilting box, comprises a front flange 8, a shorter rear flange 12, and a bottom 10. Preferably at the left the bottom 10 is slotted to provide two upstanding parallel flanges 194 and 196 through which a shaft 198 passes. A pulley 200 is rotatably mounted on this shaft. In addition, the bottom 10 between the upright plates 194 and 196 is provided with a hole 202 through which the lifting rope 162 passes to engage over the pulley as shown in Figure 13.

In addition, a transverse partition 204 is arranged. This partition is provided with a flange 206 which is preferably spot welded to the rear wall 12 of the box and in addition the partition 204 has a bottom flange 208 which is held by

means of self-tapping screws 210 to the bottom 10 of the header box. The partition is provided as at 212 with a hole through which the rod 66 passes. This hole provides a bearing for permitting the rod 66 to turn therein.

5 A portion of the bracket 204 is folded upon itself as at 214, see Figure 12, to provide spaced plate-like members 216 and 218 to receive a shaft 220 upon which a pulley 222 is rotatably mounted. By reference to Figures 12, 13 and 10 14 it will be seen that the parallel folded portions 216 and 218 of the housing or bearing for the pulley project downwardly through an opening 224, see Figure 14, formed in the bottom plate 10 of this lifting box. These housing plates 216 and 218 provide a guide for the two cords as hereinafter described. The pulley 222 is shown in Figure 14 as comprising a double pulley arranged at a proper angle so as to receive the two cords 226 and 228. As shown in 15 Figure 13 the lifting cord 226 comes from the smaller pulley 166 which is mounted in the tilting box, and this cord 226 passes onto one of the pulleys 222. In addition the other lifting cord 228 first passes upwardly through the hole 25 in the bottom wall of the raising box and then around the pulley 200 and thence passes over the other pulley 222 as shown in Figure 13. Thus these pulleys 222 must be disposed at a proper angularity to receive the cords 226 and 20 228 from the pulleys 200 and 166 and similarly must be disposed so that the cords will be directed downwardly through the hole 224 in the bottom of the box, the two parallel guide walls 216 and 218 passing downwardly through the 25 bottom of this box and having tongue portions, the lower edges of these parallel plates being preferably flared outwardly as at 231 to eliminate friction. It will be noted that the projecting ends of these parallel plates which pass 30 through the hole 224 in the bottom of the lifting box are disposed to the rear of the front panel 52 and thereby maintain the ornamental appearance of the front panel while at the same time bringing the control of the lifting cords to the front of the box.

45 Pivotedly mounted between the two plates 216 and 218 is a latching pawl 234 pivotally mounted on a pin 236 and having a serrated forward edge 238. This latching pawl is formed of a 50 flat piece of sheet metal and has a flat portion 240 and two side flanges 242 and 244. In addition, a T-headed end 246 abuts against the parallel side flanges 216 and 218 so that the pawl 234 is retained in proper position to pivot 55 about the pin 236. The serrated edge 238 clips the lifting cords so that when they are shifted a downward pull on the cords will allow disengagement of the teeth 238 and will permit the operator to lower the blind. The teeth 238 grip the cords between the edges of the teeth and the back wall 214 of the housing. The 60 manner of operation of the raising and lowering of the blind by operation of the cords 226 and 228 is of the usual arrangement.

65 The means for holding the tilting tapes 116 and 118 on the tilting heads is shown in Figures 16 to 21 inclusive. In general this means comprises a sheet metal bracket 242 which is bent as at the bottom in square fashion as at 244 snugly to engage the elongated rod 66 and is fastened frictionally in place on this rod by a self-tapping screw 246 which passes through the registering opening 248. The upper portions 70 250 and 252 of each bracket are bent down-

wardly in curved formation as at 254 and 256 to provide two smooth curved surfaces over which the top portions of the tilting straps 116 and 118 lie. These curved surfaces 254 and 256 are shown in perspective in Figure 16. Means is provided for detachably securing the upper portions of these two tapes to the tape brackets and this preferably takes the form of a peculiarly fashioned, hairpin-like wire 257 shown in Figure 21, which comprises a head portion 258, the opposite ends of which are bent inwardly at 260 and 262 to provide two elongated, substantially parallel legs 264 and 266 the extreme ends of which are outwardly bent to provide parallel portions 268 and 270 which portions are resilient. The head 258 is disposed so that its extreme ends 272 and 274 are confined in horizontal slots 276 and 278 formed in the edges of the upwardly folded portions 250 and 252 of the bracket. In addition, a stop member 280 is adapted to lie resiliently against the cross bar 258 of this hairpin-like fastener to hold it in place. This stop member is preferably of sheet metal and comprises a tongue upstanding from the square portion 282 of the sheet metal box 280 which is welded as at 284 to the rod 66. Each shank 264 and 266 of this fastener passes through a loop portion 286 and 288 of the straps 116 and 118 and then the free ends 268 and 270 of the fastener, after being pressed inwardly, will spring outwardly and lie in and engage with the notches 290 and 292 formed in the opposite edges of the straight portions 250 and 252 of the curved members 254 and 256. By pinching inwardly upon the two free ends 268 and 270 and then swinging them upwardly, the two tapes can be taken off the fastener.

Obviously the invention is not limited to the specific details of construction disclosed herein but is capable of other changes and modifications without departing from the spirit and scope of the appended claims.

Having thus described my invention, what I claim as new and desire to secure by Letters Patent is:

1. A head box construction for a Venetian blind comprising right and left supports, slat tilting means mounted on one of said supports, slat lift cord controlling means mounted on the other support, removable panel means for rigidly interconnecting the backs of said right and left end supports, and other panel means removably supported on the front of said right and left supports and forming a substantially enclosing housing for the front of said tilting and controlling means.

2. A head box construction for Venetian blinds comprising right and left hand spaced apart supporting units, each including a pair of parallel front and back walls and a transverse interconnecting wall, slat tilting means mounted on the walls of one of said supporting units, lift cord controlling means mounted on a wall portion of the other supporting unit, removable panel means rigidly interconnecting said back walls, and a front panel removably supported by and spanning the space between said front walls and forming with the right and left hand support units a substantially enclosing housing for the means mounted on said right and left hand support units.

3. A head box construction for a Venetian blind comprising a pair of end brackets adapted to be connected to spaced positions adjacent the

top of a window structure, a pair of sheet material supports each including two spaced substantially parallel front and rear walls and an interconnected transverse wall, slat tilting mechanism operatively mounted in the walls of one of said supports and slat lifting and lowering mechanism mounted in the walls of the other of said supports, said supports being spaced apart, a rigid, elongated separate panel interconnecting the rear walls of said supports, one end of each of said supports overlying a portion of each end bracket, and means for adjustably and detachably fastening one end of each support to the adjacent one of said end brackets, an elongated blind carrying member having its ends mounted in each one of said supports including connections whereby said elongated blind carrying member is operated by said slat tilting mechanism, strap connectors mounted on said carrying member in spaced relation thereon and turnable therewith, and an ornamental front panel adapted to span the space between said brackets, said panel having means whereby the same may be detachably fastened to the said front walls of said supports.

4. In combination, a pair of end brackets comprising sheet metal end wall members and upper and lower integrally formed, horizontally extending members and a back vertical member, the front edge of said end member being disposed at a predetermined lateral inclination, the lower horizontally extending member having a slot therein provided with a guide portion formed on the same predetermined inclination as the inclination on which the front edge of the end member is formed, a pair of head boxes each comprising a bottom support one end of which is adapted to overlie the slotted horizontal lower wall of an end bracket, said bottom wall of each of said supports having an opening, fastening means adapted to pass through the slot and into said opening whereby adjustably to secure the boxes to the end members, separate means for rigidly interconnecting said boxes, and an ornamental front panel having its ends adapted to overlap the front ends of the end brackets, the ends of the front panel being formed on a similar inclination to that of the inclination front edges of the end brackets whereby to permit limited adjustment of the head boxes and front panel relatively to the end brackets while maintaining a snug fit between the ends of the front panels and the end brackets.

5. A tilting box for a Venetian blind comprising a first support and a second support, panel means to interconnect and rigidify said supports, tilting mechanism mounted in the first support comprising a sector turnably mounted on said support, an inclined driving drum, a shaft for driving said drum, said shaft and drum having a common axis inclined to the horizontal, the lower end of said shaft carrying a pinion meshing with the teeth of the sector, a cord guiding pulley mounted on the base of said first mentioned support, a cord guiding pulley mounted on the base of the second support, said second support having a bearing, said second mentioned support having spaced inclined walls parallel to the longitudinal axis of said second support but tilted with respect to a vertical plane passing therethrough, an elongated actuator connected to said sector and mounted in the bearing of said second mentioned support, a projection of the axis of said elongated actuator being disposed relatively close to the upper portion of said tilted

11

walls, and a pair of guide pulleys rotatably mounted in said tilted walls, said second mentioned support at its base having an opening through which said tilting walls project, a tilting cord windingly mounted upon said drum, and lifting cords passing around the guide pulley on the first support and around the guide pulley of the second support and around the pulleys confined between said laterally tilted walls, and the ends of said cords passing downwardly through the bottom of said second mentioned base adjacent the front part thereof.

6. A raising and lowering box for a Venetian blind comprising a sheet metal support having a bottom wall and transversely spaced integral upstanding front and rear walls, a bearing disposed between said spaced walls, the bottom wall of said support having portions thereof slotted and bent upwardly to provide upstanding inner walls, a guide pulley pivotally mounted between said inner walls, the bottom wall adjacent said pulley having a cord opening, a guide strip folded upon itself to provide spaced apart bearings and projecting through said opening, a pair of pulleys rotatably mounted in said bearings and between said front and rear walls, the axis of said pulleys being inclined with respect to the bottom and front walls, and an ornamental panel mounted upon the front wall of said box whereby cords passing around said guide pulley and around said pair of pulleys will project downwardly out through the bottom of said box to the rear of said front panel.

7. In a Venetian blind construction, a bottom rail construction comprising upper and lower elongated shell-like sheet metal halves having laterally extending flanges in parallel disposed relation, the flanges of said halves being adapted to telescope in parallel relation to form a shell closed at the sides, top and bottom, end caps adapted to fit over the ends of said shells, and tapes passing between the interfitting flanges of said shells, and a pair of lifting cords having their lower ends passing through the upper one of said upper shell halves and having an enlarged section within said rail preventing withdrawal of said cords.

8. In a Venetian blind, in combination with a tilting box having tilting mechanism therein and a slat raising and lowering box having slat raising and lowering mechanism therein, an elongated rod of non-circular cross section extending between said boxes, the tilting mechanism in said tilting box turning said rod, sheet metal members having a portion adapted to fit about said rod, there being means for fastening the sheet metal members in slidably position along said rod within each of said tilting boxes, said members having opposed branches on each side of said rod with outwardly turned flanges on the ends of the branches, tilting straps overlying said flanges, the edges of said branches

12

being notched adjacent said flanges, an elongated wire fastener having a folded head, the opposed shanks of which, adjacent the head, lie in part of said notches, the head lying transversely of the ends of said branches, each of said shanks being adapted to receive the folded end of a strap therethrough, whereby to hold the ends of the straps to the tilting mechanism, the opposite end of the elongated shanks having outwardly extending shoulder portions which may be pressed together and upon release resiliently spring outwardly into other of said notches to hold the fastener in position thereon, and means mounted on said angularly disposed rod comprising an upstanding arm adapted to engage the cross portion of the head to hold the same in position.

9. In a Venetian blind, the combination with a tilting box having slat tilting mechanism therein and a slat raising and lowering box having slat raising and lowering mechanism therein comprising, a rod having portions of its length non-circular of cross section extending between said boxes, the tilting mechanism in said tilting box being connected to said rod to turn the same, folded sheet metal clips having a portion fitted about said rod, means for fastening said clips in position along said rod and within each of said boxes, said clips having opposed branches on each side of said rod with outwardly turned flanges on the ends of the branches, tilting straps overlying said flanges, the edges of said branches being notched adjacent to said flanges, an elongated wire fastener having a folded head associated with each clip, the opposed shanks of said fasteners adjacent the heads thereof lying in part of said notches with the head lying transversely of the ends of said branches, each of said shanks being adapted to be passed through the folded end of said tilt straps whereby to hold the ends of the straps to the clips, the opposite ends of the shanks having outwardly extending shoulder portions springably engaged in others of said notches to hold said fasteners in position.

GLENN L. SHERWOOD.
